(57) **CLAIM**

The ornamental design for a waist trimmer, as shown and described.

DESCRIPTION

FIG. 1 is a front elevation view of a waist trimmer, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front and top perspective view thereof;

FIG. 8 is another perspective view thereof, shown in an alternative position; and,

FIG. 9 is another perspective view thereof, shown in an alternative position.

The broken lines in the figures illustrate portions of the waist trimmer that form no part of the claimed design.
